Specification of Letters Patent.

Patented Oct. 6, 1914.

Application filed September 23, 1910. Serial No. 584,190.

To all whom it may concern:

Be it known that I, JOSEPH WHITE, a citizen of the United States, residing at Beechwood Heights, Piscataway township, Middlesex county, (whose post-office address is Boundbrook) State of New Jersey, have invented certain new and useful Improvements Relating to Printing-Presses.

This invention has for its object improved tripping mechanism, particularly adapted for tripping the cylinders of printing presses.

While some of the features embodied in this invention may be used in various types of printing machines, the invention is adapted more particularly for that type illustrated in the accompanying drawings, which has an impression cylinder containing a plurality of impression surfaces, and adjacent to said cylinder are located a plurality of form cylinders, the forms of which co-act with the impression surfaces on the impression cylinder to produce multi-color impressions. During the printing operation the axes of these cylinders remain at a fixed distance from each other, but when it is desired to interrupt the printing operation, the cylinders are moved apart and rotate out of contact with each other.

Referring to the drawings: Figure 1 is an elevation showing so much of a printing machine as is necessary to illustrate the features of this invention. Fig. 2 is an elevation showing the parts in a different position from that shown in Fig. 1. Fig. 3 is a plan view of Fig. 1.

1 and 2 are the side frames of the machine in which is mounted the fixed bearings of the impression cylinder 3, which has formed upon its surface preferably two impression surfaces, 4 and 5; said impression surfaces each having a set of sheet-taking grippers 6 and 7 at their leading edges (said grippers being located in the impression cylinder gaps 19 and 20 between the impression surfaces), by which means the sheet is taken from the feedboard 8 in the usual manner and placed upon the impression surfaces.

Adjacent to and co-acting with the impression cylinders are a plurality of form carrying cylinders (two in the form shown for purposes of illustration), which are

journalized in eccentric bearings mounted in the side frame of the machine. These form carrying cylinders support form surfaces 17 and 18 which occupy the major portion of the periphery of the cylinder, the unused portions of which consist of form cylinder gaps 21 and 22. Referring to the plan view of the machine it can be seen that these cylinders are connected by a train of gearing, which in this particular type of machine give the cylinders constant rotation; this train consisting of form cylinder gears 11 which mesh with impression cylinder gear 12, said gear 12 receiving its motion from pinion 13 which is fastened to the driving shaft 14 of the machine; said shaft being connected to the source of power in the usual manner.

During the normal printing action the sheets are taken from the feedboard 8 by the grippers 6 and 7 and as the sheets upon each impression surface pass the form cylinders, they receive the first color from the form 17 and the second color from the form 18; thus for each rotation of the impression cylinder two sheets are printed with two colors each.

For the various necessary purposes known in the art of printing it is desirable to trip the cylinders out of printing relation with each other without stopping the machine, and when this operation is performed in a machine of the type illustrated, it is desirable to place the cylinders into printing relation in such a manner that a sheet which has been presented to the impression surface will receive its full impression from both cylinders; and also when the cylinders are tripped it is necessary that they are placed into printing relation in such a manner and at such a time that the form and impression surfaces do not contact with one another when no sheet is upon an impression surface. This is accomplished by arranging the mechanism so that the action of moving the cylinders into and out of relation with each other is accomplished in the proper sequence, during the time that the cylinder gaps are passing one another. The mechanism for this purpose is as follows: Each of the form cylinders is provided with a cylinder-moving means which constitutes that part of the mechanism which is directly con-

neeted to the eccentric bearings of the cylinders, and moves with said bearings, and consists of the following parts: The pair of eccentric bearings 9 have fastened to them on the inside of the frame, a pair of eyes 23 which serve to hold the boxes laterally in the frame. Fastened to these eyes are pins 24 in which are pivotally mounted connections 25, the other end of which is pivoted on pins 26 which are fastened to arms 27 which are formed on hubs 28 which are fastened to the rockshaft 29. Likewise the eyes 30, pins 31, connections 32, pins 33, arms 34, hubs 35 and rockshaft 36 serve a similar function to the second cylinder. It can be seen that when the shafts 29 and 36 are rocked in one or the other direction, they will move their respective cylinders into or out of printing relation with the form cylinder. The hub 28 has formed upon it a pair of forked arms 37 and 38 in which are mounted pins 39 and 40; and the hub 35 has formed upon it a pair of forked arms 41 and 42 in which are mounted pins 43 and 44.

The manner in which the cylinder-moving means is actuated so as to trip the cylinders during the time the cylinder gaps are passing each other is as follows: It can be seen by referring to the impression cylinder that it is so proportioned that the impression surfaces occupy each about three-eighths of the circumference of the cylinder, and the gaps between them occupy a little more than one-eighth of the circumference. Now, by arranging an actuating mechanism which will perform a movement to trip the cylinders during one-eighth of the revolution of the impression cylinder, it will accomplish the tripping operation while the gaps are passing each other: and if when the cylinders are tripped and this movement is utilized for the purpose of restoring the impression at the same portion of the rotation of the cylinder, it will throw the cylinders into impression while the gaps are passing one another. The mechanism for accomplishing this preferably includes actuating members which are caused to make a plurality of complete reciprocations (in this case four) to each rotation of the impression cylinder, or to each cycle of operations of the machine; a forward movement only of a reciprocation (which takes place in one-eighth of one revolution of the impression cylinder) is utilized for the purpose of moving the cylinders into impression position when it is tripped, and for tripping the cylinder when it is in printing relation. Means are connected to the actuating members to properly time their operation upon the cylinder-moving means to move the form cylinders in proper sequence while the gaps are passing each other.

While the actuating members may be moved in various ways, it is done preferably

in the following manner: The pinion 13 has meshing with it a gear 45 which is one-quarter the diameter of cylinder gear 12 and makes four revolutions to one of the impression cylinder. This gear 45 is mounted on stud 46 fastened in the side frame of the machine, and formed on this gear is an eccentric 47; said eccentric engaging actuating arm 48 and causing it to make four complete oscillations to each revolution of the impression cylinder, or a forward oscillation in one-eighth of a revolution of the impression cylinder.

Referring to Fig. 1, the position of the parts show the cylinders in tripped position; the impression surface 5 and form surface 17 have just passed the printing point, and the actuating fork 48 has just about completed one of its return or idle strokes. In a manner hereinafter to be described, the actuating fork 48 will now be raised, causing the projection 89 to engage the pin 40, and the continued movement of the eccentric will now cause the actuating fork to make its forward stroke, moving the parts to the position shown in Fig. 2, in which case the form cylinder has been moved into printing relation with the impression cylinder, and the front edge of the impression surface 4 has just reached the printing point and the impression will now be taken upon the sheet of paper which is held by the grippers 6. As long as the actuating fork 48 is held in this upper position as shown in Fig. 2 it will oscillate idly back and forth without operating to move the cylinder, and the form cylinder will be maintained in printing relation with the impression cylinder.

The setting and timing means for controlling the movement of the actuating fork 48 so that it becomes operative at the proper reciprocation is manually operated and includes a guard whereby the operation is controlled so as to time the positioning of the actuating fork so that it will be operative only at the time the cylinder gaps are passing one another.

Fastened in the actuating fork 48 is a pin 49 which passes through the eye of a connection 50; said connection passing through a swivel 51 which is fastened on a segment gear 52; said segment gear being mounted on a stud 53 which is fastened in the rear side frame 2 of the machine; said segment gear 52 meshes with another segment 54 which is fastened to a shaft 55, said shaft being mounted in the front and rear frames of the machine. Just inside the front frame a lever 56 is fastened on this shaft to the other end of which is pivoted a connection 57 which has a slotted hole 58 through which passes a pin 59. This pin 59 is fastened in a lever 60 inside the front frame, and is connected to a short shaft 61 which passes through the front frame and on the outer end is foot 130

treadle 62. When this foot treadle is depressed, the segment 52 is rocked and raises swivel 51, causing the connection 50 and actuating fork 48 to be raised and hold the fork 48 in its lifted position against the pin 40 throughout its entire movement, and to compensate for the varying distance between the pin 49 and the swivel 51, the connection 50 is provided with a spring 63 against 10 which the swivel 51 acts and presses upon the washer 64 on the end of the connection 50.

In order that the fork will not be raised or lowered at any other time but when the 15 cylinder gaps are passing one another, a rotating guard is provided which controls the time that this mechanism can be operated. This guard may be placed in any suitable or 20 convenient manner and operated in various ways, but preferably consists of segments of rings 65 and 66 which are fastened to the impression cylinder. (As the impression cylinder has two impression surfaces and two gaps, two guards are necessary, as can 25 be seen.) Loosely mounted on the outer end of the pin 59 is a roller 67 which projects into the planes of the guards 65 and 66 which controls the time it can be moved; when the treadle 62 is pressed and a guard 30 gap passes the roller 67, it is moved upward to the position shown in Fig. 1; The pin 59 moves from a position at the bottom of the slot 58 to the top of the slot and the treadle-toe 82 is caught under the first notch 35 69 of the latch 70 (as shown in Fig. 1). It will be noted that the manual movement of the treadle places the same on a level with the footboard 71; said treadle passing through a pocket provided in the footboard. 40 The guard 65 has a cam point 68 upon which the roller 67 is raised (see Fig. 2), causing it to move the connection 57 and rock the shaft 55 and segment gears 54 and 52, thus raising the actuating fork 48 which 45 engages the pin 40 to throw the form cylinder into impression. When the roller 67 rides upon the cam point 68, it raises the lever 60 and depresses the treadle 62, causing the toe 82 to be caught under the second 50 notch 72 of the latch 70 which serves to hold the setting mechanism in such a position whereby actuating fork 48 is held against the pin 40.

Referring to Fig. 1, the guard roller 67 55 has just passed through the gap between the guards and has been raised to the cam point 68 and the actuating fork 48 is therefore just about to be raised to engage the pin 40, it being just about at the end of its return 60 stroke. The impression surface 5 and the form surface 17 have just passed one another, and the gaps are now passing one another, and the forward stroke of the fork 48 will act upon the rockshaft 29 as has been 65 previously described to move the cylinders

into printing relation during the time the gaps are passing one another. The parts have now taken the position shown in Fig. 2.

The second cylinder-moving mechanism is provided with actuating means similar to 70 the first cylinder, and consists of an actuating fork 73 which is engaged by an eccentric or crank disk 74 which is bolted to the gear 45. As has previously been mentioned in relation to actuating fork 48, the actuating fork 73 is effective upon the pins 43 and 44 to move the form cylinder 16 into and out of printing relation with the impression cylinder at the proper time. The eccentric 74 is so placed upon the gear 45 that the forward stroke of the actuating fork 73 will 75 take place during the time the cylinder gaps are passing one another; and the particular forward oscillation which is rendered effective to move this cylinder is controlled as 80 follows: The hub 28 has formed upon it an arm 75 to which is pivoted connection 76 which passes through an eye-bolt 77 fastened to the actuating fork 73. The connection 76 has a coil-spring 78 which is placed below the 85 eye-bolt 77, said coil-spring acting against the washer on the end of the connection 76. When the shaft 29 is rocked to move the form cylinder 16 into impression through the agency of the parts previously described, 90 the spring 78 will be compressed and will tend to raise the actuating fork 73 against the pin 43; and when this fork has completed its return stroke, it will catch over the 95 said pin and in its forward stroke will act 100 to move the form cylinder 16 into impression. As has been previously described, the parts are so timed that this movement will take place during the time the cylinder gaps are passing one another; Thus it can be seen 105 that after the pressure has been thrown on, the first impression surface coating with the form surface to produce an imprint, will receive its second imprint from the second cylinder; and the cylinders will remain in 110 printing relation as long as the treadle 62 is held in its downward position by the latch 70. This latch 70 is mounted on a stud 80 upon which is a torsion spring 81, which 115 serves to hold the latch against the treadle-toe 82. When it is desirable to trip the cylinders out of printing relation the treadle 83, with which the latch 70 is provided, is depressed, causing the setting mechanism to be released and when the guard gap comes opposite the roller 67, this roller drops, causing actuating fork 48 to fall upon the pin 39, where said fork can take hold of the pin 39 in its next forward stroke and trip the cylinder 15 out of printing relation to the impression cylinder, and when the shaft 29 is rocked, the actuating fork 73 is allowed to drop upon the pin 42, and in its next forward stroke it will operate to throw the form cylinder 16 out of printing relation 125 130

with the impression cylinder: Thus it can be seen that when the impression surface misses its impression from the first cylinder, it will always be placed out of impression relation with the second cylinder; and when an impression surface is thrown into contact with the first cylinder, it will always receive an impression from the second form cylinder.

While the principles embodied in this invention are shown in connection with a multi-color press in which the form cylinders are actuated to move when the press is tripped, certain features of this invention can be applied to different types of rotary printing machines, and may be applied to a machine wherein a single printing couple is used and in which the impression cylinder instead of the form cylinder is moved when the press is tripped; and it is understood that such use is contemplated.

It is also obvious that many features of my invention will be useful for many purposes other than the tripping of cylinders in printing machines, and that they may be applied in any machine where it is desirable to move a part from one position to another and back again, at the will of the operator and in timed relation to the remaining mechanism of the machine.

What I claim is:

1. In a printing machine, a printing couple, including a cylinder mounted in eccentric bearings, connections from said bearings to a rockshaft, a member making a plurality of rotations for each cycle of operation of the machine, a crank on said member, a reciprocating bar moved by said crank and arranged to move said rockshaft in one direction to trip the cylinder, and in another direction to throw the cylinder into printing relation.

2. In a printing machine, a movable member, a pivoted oscillatable member, connections between said oscillatable member and said movable member, a reciprocatable actuating device adapted to be positioned to engage said oscillatable member at either of the two opposite sides of its pivot, means to give said actuating device a plurality of complete reciprocations for each cycle of operation of the machine, and means to position said actuating device.

3. In a printing machine the combination of a printing couple including a cylinder, movable bearings for said cylinder, a rockshaft, connections from the rockshaft to the movable bearings, projections on opposite sides of the rockshaft, a reciprocating bar acting upon the projections during its forward stroke to rock the shaft to throw the cylinder into or out of impression relation, manually controlled setting mechanism for shifting the bar, and a guard for controlling the setting mechanism to permit the bar to move only at a specified time.

4. In a printing machine the combination of an impression cylinder, two form cylinders coacting with the impression cylinder, cylinder-moving means for each of the form cylinders, actuating means for each of the cylinder-moving means, and setting means connected from the first form cylinder-moving means to the second actuating means whereby the second form cylinder is always thrown into printing relation with the impression cylinder after the first form cylinder is tripped.

5. In a printing machine the combination of an impression cylinder, two form cylinders coacting with the impression cylinder, cylinder-moving means for tripping each of the form cylinders out of printing relation with the impression cylinder, actuating means for each of the cylinder-moving means, and setting means connected from the first cylinder-moving means to the second actuating means whereby the second form cylinder is always tripped after the first form cylinder.

6. In a printing machine the combination of an impression cylinder having a plurality of impression surfaces thereon, a plurality of form cylinders coacting with the impression cylinder, cylinder-moving means for each of the form cylinders, actuating means for each of the cylinder-moving means, setting means for each of the actuating means; said actuating means each comprising a part making a plurality of reciprocations to each rotation of the impression cylinder.

7. In a printing machine the combination of an impression cylinder, two form cylinders coacting with the impression cylinder, cylinder-moving means for placing the form cylinders into and out of relation with the impression cylinder, actuating means for the cylinder-moving means; said actuating means comprising a member making a plurality of rotations to each rotation of the impression cylinder, and having two eccentricities formed upon it, reciprocating parts connected to said eccentricities, and means whereby said reciprocating parts are caused to become effective upon the cylinder-moving means to throw the form cylinders into or out of printing relation with the impression cylinder.

8. In a printing machine the combination of a printing couple, movable journal bearings for one of the cylinders of the couple, a rockshaft, connections from the rockshaft to the journal bearings, a continuously rotating crank, and a reciprocating part shiftable at one end and connected to the crank at the other end; said shiftable end engaging the rockshaft during a movement of the reciprocating part either to throw the cylinders into or out of printing relations with each other.

9. In a printing machine the combina- 130

- tion of a printing couple, movable journal bearings for one of the cylinders of the couple, a rockshaft, connections from the rockshaft to the journal bearings, a continuously rotating crank making a plurality of revolutions to each printing operation, and a reciprocating part shiftable at one end and connected to the crank at the other end, and controlling means for shifting the reciprocating part only at a specified reciprocation to engage the rockshaft either to throw the cylinders into or out of printing relations with each other.
10. In a printing machine, a movable member, an oscillatable member pivoted on a stationary part of the machine and provided with abutments located on opposite sides of the center of said oscillatable member, connections between said oscillatable member and said movable member, an actuating device mounted to reciprocate between the said abutments and formed with shoulders for engagement with said abutments, means to give said actuating device a plurality of complete reciprocations for each cycle of operation of the machine, and means to position said actuating device to engage with one or the other of said abutments.
15. In a printing machine, a movable member, a rock shaft, connections between said movable member and said rock shaft, abutments carried by said rock shaft and located on opposite sides of the center thereof, an actuating device mounted to reciprocate in between the said abutments and formed with shoulders for engagement with said abutments, means to give said actuating device a plurality of complete reciprocations for each cycle of operation of the machine and means to position said actuating device to engage one or the other of said abutments.
20. 11. In a printing machine, a movable member, an oscillatable member pivoted on a stationary part of the machine, connections between said movable member and said oscillatable member, a continuously rotating crank, a reciprocating part shiftable at one end and connected to said crank at the other end and means to position said shiftable end to cause it to engage and turn said oscillatable member on a forward movement of said reciprocating part.
25. 12. In a printing machine, a movable member, an oscillatable member pivoted on a stationary part of the machine, connections between said movable member and said oscillatable member, a continuously rotating crank, a reciprocating part shiftable at one end and connected to the crank at the other end and means to position said shiftable end to cause it to engage and turn said oscillatable member on a forward movement of said reciprocating part.
30. 13. In a printing machine, a pair of movable members, moving means for each of said movable members, each of said moving means including an oscillatable member, a pair of reciprocating parts each shiftable at one end, manually operated means to shift the first of said shiftable ends to cause it to engage the first of said oscillatable members and connections between the first of said oscillatable members and the second reciprocating part, adapted and arranged to shift the second of said shiftable ends to cause it to engage with the second of said oscillatable members.
35. 14. An impression cylinder, a plurality of form cylinders connecting therewith, cylinder moving means for each said form cylinder arranged to trip it out of printing relation with said impression cylinder, actuating means for each said cylinder moving means, a rotatable member arranged to make a plurality of rotations for each rotation of said impression cylinder, connections between said rotatable member and said actuating means and between the several actuating means, so constructed and arranged that each said actuating means moves its cylinder moving means during a predetermined rotation of said rotatable means.
40. 15. An impression cylinder, a plurality of form cylinders connecting therewith, cylinder moving means for each said form cylinder arranged to trip it out of printing relation with said impression cylinder, actuating means for each said cylinder moving means, a rotatable member arranged to make a plurality of rotations for each rotation of said impression cylinder, connections between said rotatable member and said actuating means and between the several actuating means, so constructed and arranged that said actuating means move their respective cylinder moving means in succession and during successive predetermined rotations of said rotatable means.
45. 16. An impression cylinder, a plurality of form cylinders arranged to coact with said impression cylinder, cylinder moving means for each said form cylinder arranged to trip it out of printing relation with said impression cylinder, actuating means constructed and arranged to operate on each said cylinder moving means and mechanism constructed and arranged to give a plurality of operative movements to said actuating means for each rotation of said impression cylinder.
50. In witness whereof, I have hereunto set my hand in the presence of two subscribing witnesses.
